DESIGN FOR A SACHET CONTAINER

Paul H. Ganz, New York, N. Y.

Application September 21, 1935, Serial No. 58,637

Term of patent 7 years

To all whom it may concern:

Be it known that I, Paul H. Ganz, a citizen of the United States and a resident of the city, county, and State of New York, have invented a new, original, and ornamental Design for a Sachet Container, of which the following is a specification, reference being had to the accompanying drawing, forming part thereof.

Figure 1 is a front elevation of a sachet container showing my new design; and

Figure 2 is a plan view thereof.

The characteristic feature of my design is the cross hatching effect apparent in the equatorial region in the showing of Figure 1 and which is due to the crossing of the twistless threads of superposed layers of threads at a slight angle to each other.

I claim:

The ornamental design for a sachet container, as shown and described.

PAUL H. GANZ.
